THREAD TENSIONING DEVICE

Frank B. Javery, Worcester, and Armon J. Javery, Oxford, Mass., assignors to Warp Compressing Machine Company, Worcester, Mass., a corporation of Massachusetts

Application July 24, 1933, Serial No. 681,856

4 Claims. (Cl. 242—154)

The present invention relates to a thread tensioning device for use in connection with winding machines, and has for its object to provide a device that is adapted to maintain a uniform tension on the thread for proper winding.

A further object of the invention is to provide a tensioning device which will be extremely sensitive to variations in the pull on the thread, and which will automatically relieve the tension normally maintained on the thread upon the occurrence of any abnormal condition tending to increase the pull on the thread. The above and other advantageous features of the invention will hereinafter more fully appear from the following description with reference to the accompanying drawings, in which:

Fig. 1 is a perspective view of a thread tensioning device embodying the invention.

Fig. 2 is a plan view of the device shown in Fig. 1.

Fig. 3 is a view in front elevation, showing the device in its normal thread tensioning position.

Fig. 4 is a view similar to Fig. 3, showing the tensioning members in position for relieving the tension in response to an increase in the pull on the thread.

Figs. 5 and 6 are views in front elevation and plan respectively, of a modified form of the device.

Figs. 7 and 8 are fragmentary views illustrating parts of the device of Fig. 5.

Like reference characters refer to like parts in the different figures.

Referring first to Fig. 1, the device of the present invention is adapted to apply a substantially uniform tension to a thread passing from a package 1 to any suitable winding apparatus, not shown, the tensioning device being particularly suitable for use in connection with a creel. The tensioning device is shown mounted on a horizontal support 2, with a vertical portion 3 carrying a thread guide 4, with a second thread guide 5 positioned at the front of the support 2 to direct the thread to a suitable winding apparatus after passing through the tensioning device, see Figs. 2 and 3.

The tensioning device consists of a bracket 6 mounted on the support 2, the ends of the bracket 6 carrying a pin 7 on which are pivotally mounted two sets of tension members 8 and 9. The tension members 8 of one set extend in spaced relation from the pivot pin 7, with their free ends bent downwardly at 8a so as to rest on the support 2. The general level of the several members 8 between pivot pin 7 and their end portions 8a is slightly above the opening in the thread guide 4,

as shown in Fig. 3. The other set of tension members 9 also extend in spaced relation from the pivot pin 7, with their free ends bent upwardly at 9a and resting on the support 2, so that the general level of the members 9 is below the opening in the thread guide 4. In the absence of any other force acting on the tension members 8 and 9, they normally extend in substantially parallel relation above and below the plane of the thread guide 4.

As best shown in Figs. 1 and 2, the tension members 8 and 9 are alternately arranged on the pivot pin 7 so that their oppositely bent end portions 8a and 9a intersect each other, as viewed in elevation, the threading of the device being readily accomplished by placing the thread between the intersecting ends and drawing it into alignment with the thread guide 4. Upon the thread being released following the threading operation, the tension members 9 all tend to resume the position shown in Fig. 3, from which it is evident that normally the thread follows a sinuous path between the alternately spaced members 8 and 9 in passing from the thread guide 4 to the thread guide 5.

As the thread is drawn to the winding apparatus through the tensioning device, it is subjected to a retardation, or drag, as it passes over and under the tension members 8 and 9, thereby maintaining the proper tension on the thread for winding. This condition is clearly illustrated in Fig. 3, and generally speaking, is maintained so long as the thread passes freely through the thread guide 4 from the package 1. If, however, for any reason the thread does not unwind freely from the package 1, or is subjected to any other retarding effect in its passage to the tensioning device through the guide 4, the increased draft on the thread will be automatically relieved before it becomes so great as to break the thread. Owing to the fact that each tension member 9 is freely mounted on the pivot pin 7 independently of all the other members 8 and 9, any appreciable increase of the draft on the thread will quickly result in moving one or more of the members 9 upwardly to the position shown in Fig. 4, thereby relieving the tension on the thread by providing a more direct path for the same as it passes between the thread guides 4 and 5. Obviously, the upward movement of any one or more of the tension members 9 in response to an increase in the draft on the thread may be only momentary, the members 9 returning to their normal position of Fig. 3 as soon as the outside retarding force on the thread is removed. In

order to prevent the tension members 9 being thrown upwardly too far, in response to a very sudden increase in the draft on the thread, a stop 10 is provided to limit upward movement of 5 the members 9 beyond the position of the uppermost member 9 shown in Fig. 4; in this position, this member 9 is above the level of the thread guide 4.

Referring now to Figs. 5 to 8 inclusive, there 10 is shown a modified form of tensioning device, in which the tension exerting members are extremely sensitive to changes in the draft on the thread, by reason of the fact that certain of these members are more readily lifted to relieve 15 the pull on the thread than are the others. In Fig. 5 the tension members 11 are pivotally mounted on a shaft 12, and are formed in substantially the same manner as are the tension members 8, with their free ends bent downwardly 20 at 11a so as to rest on the bracket 13. Alternately mounted on the shaft 12 between the tension members 11 are two sets of cooperating tension members 14 and 15 respectively, these members being shown as removed from the shaft 12 25 in Figs. 7 and 8.

The tension members 14 are each constructed in substantially the same manner as are the members 9, shown in Fig. 3, with their free ends bent upwardly at 14a and resting on the bracket 30 13. The other members 15 extend downwardly from the level of the shaft 12 at a steeper angle than do the members 14, with their free ends bent upwardly at 15a and resting on the bracket 13 at a greater distance from the shaft 12 than 35 do the portions 14a. As a result of the different inclinations of the members 14 and 15, it is clearly evident from Fig. 5 that the thread in passing around adjacent members 11 and 14 has considerably farther to go than in passing around 40 adjacent members 11 and 15; as a consequence of which the members 15 will be lifted to the level of the members 11 in response to a lighter pull.

Furthermore, in order to render the members 15 even more sensitive to changes in the pull on the 45 thread, one or more of the members 15 is counterbalanced with reference to its pivotal axis. One way of accomplishing such counterbalancing is by providing the members 15 with integral extensions 16 on the side of the pivot shaft opposite to the thread engaging portions of the members. As clearly shown in Fig. 6, the tension member 15 nearest the thread receiving guide 17 is counterbalanced to a greater extent than are the members 15 farther removed from 50 the guide 17, so that a very slight increase in the pull on the thread will result in the tension members 15 nearest the guide 17 being lifted. Although the tension on the thread increases as it is drawn through the device, the weights of the 55 counterbalances on the successive members 15 preferably decrease at a greater rate than the increase in thread tension, and thus, during the normal operation of the device, the members 15 nearest the guide 17 will exhibit a tendency to move up and down more or less continuously in response to slight variations in the draft on the 60 thread. On the other hand, the tension members 14 nearest the delivery guide 18 will be lifted only in response to a sudden and relatively large 65 increase in the draft on the thread such as would be caused by a snarl or catching of the thread on the package 1 from which it is being withdrawn. The net result of the differential operation of the members 14 and 15 in response to 70 75 varying pulls on the thread, is the maintenance

of a substantially uniform tension on the thread as it leaves the delivery guide 18 for winding on a creel or any other disposition thereof.

In certain cases the weights of the counterbalances on successive members 15 may not decrease at as great a rate as the increase in tension on the thread as it passes each successive member. In this event, the counterbalances render the device extremely sensitive since the members 15, when counterbalanced, respond to 10 very slight variations in tension on the thread, the counterbalancing obviously being greatest where the tension is least.

As best shown in Fig. 5, the receiving guide 17 is preferably formed of bent wire with an eye 15 portion located considerably above the level of the tension members 11, 14 and 15, so that the thread passes downwardly at a steep angle to the first tension member 15. As a result of the disposition of the guide 17 at this level, the effect of 20 ballooning of the thread as it is unwound from the package 1 is not transmitted to that portion of the thread extending between the tension members, as might be the case with the receiving guide located between the tension members, as 25 shown in Fig. 3. It is also to be noted that a portion 19 of the wire from which the guide 17 is bent extends parallel to the shaft 12 and adjacent thereto so as to serve as a stop for limiting upward movement of the members 14 and 15. 30

From the foregoing, it is apparent that by the present invention we have provided a thread tensioning device that normally maintains a uniform tension in the thread for proper winding, the device being extremely sensitive to variations 35 in the pull on the thread so as to automatically relieve the tension upon the occurrence of any abnormal condition external to the tensioning device which tends to exert a retarding effect on the thread. 40

We claim,

1. A yarn tension device comprising two sets of tension members alternately arranged with each of the members of one of said sets being separately pivotally mounted for individual movement 45 toward and away from the members of the other set.

2. A yarn tension device comprising two sets of tension members alternately arranged with each of the members of one of said sets being separately pivotally mounted for individual movement toward and away from the members of the other set, and means to limit the movement of 50 said movable members in one direction of movement.

3. A yarn tension device comprising two sets of tension members alternately arranged, each of the members of one of said sets being separately pivotally mounted for individual movement toward and away from the members of the other set, said pivotally mounted members being normally maintained in maximum thread tensioning position by the weight of said members, and means to counterbalance to varying degrees the weight 60 of certain of said members.

4. A yarn tension device comprising two sets of tension members alternately arranged, each of the members of one of said sets being separately pivotally mounted for individual movement toward and away from the members of the other set, said pivotally mounted members being separately urged, to varying degrees, into maximum 70 tensioning position.
